UNITED STATES PATENT OFFICE.

FRANK H. SADLER, OF ATTLEBOROUGH, MASSACHUSETTS.

DESIGN FOR A JEWELRY-TRAY.

SPECIFICATION forming part of Design No. 26,459, dated December 29, 1896.

Application filed November 6, 1896. Serial No. 611,301. Term of patent 3½ years.

To all whom it may concern:

Be it known that I, FRANK H. SADLER, of Attleborough, in the county of Bristol and State of Massachusetts, have invented and produced a new and original Design for a Jewelry-Tray, of which the following is a specification, reference being had to the accompanying drawings, showing a part thereof.

Figure 1 is a perspective view of a jewelry-tray, showing my design. Fig. 2 is a perspective view of a jewelry-tray, showing my design as it appears when the tray is placed on a flat surface.

The leading feature of my design consists in the resemblance of the tray to the conventional form of a seal-ring, the ring proper forming the support of the tray.

In the drawings, *a* indicates the rectangular frame of the tray; *b*, a raised cushion-like

surface; *c c*, a series of slotted depressions 20 extending transversely across the face of the cushion-like surface. From each side of the rectangular frame *a* extend the lapels *d* to the ring *e*, giving to the tray the appearance and conventional form of a seal-ring. When 25 placed on a flat surface, the tray is supported in an inclined position by the ring, as is shown in Fig. 2. The ring *e* may be used to surround a bar or post and thus support the tray.

What I claim is—

The design for a jewelry-tray herein shown and described.

In witness whereof I have hereunto set my hand.

FRANK H. SADLER.
